INDENTED PAPERBOARD ARTICLE

George E. Bomberger, Indianapolis, Ind., assignor
to Inland Container Corporation, Indianapolis,
Ind., a corporation

Application March 30, 1934, Serial No. 718,104

19 Claims. (Cl. 229—3.5)

This invention relates to a paper board and a container therefrom.

Heretofore in the industry in the making of fibre board boxes, as distinguished from cardboard boxes, the boxes have been made usually from the single sheet of fiber board that is suitably scored, slotted or slitted, and then bent and secured suitably for shipment in the flat for setting up by the purchaser of the boxes, who uses 10 boxes as a container for various articles of merchandise and particularly for the shipment of canned goods and certain fragile articles. This board in the past has been either of one or two kinds—either a so-called solid fibre or pasted 15 ply board or a corrugated board.

The so-called pasted ply or solid fibre board consists of an inside and outside liner or ply of fairly good paper—that is, one having fairly good bending qualities and which has a reasonable 20 Mullen and tear test. The intermediate portion consists of a solid sheet of a chip character that is run through a silicate bath and then the liners are applied, resulting in the solid fibre board which is then cut to length or size to form sheets 25 which are subsequently scored, slotted and slitted to form the box blank or which blanks are formed directly from the sheet as it is manufactured in a so-called continuous production process.

The railroad classifications specify that in addition 30 to the Mullen test requirement, which is a "pop" test, that this solid fibre board be run to certain minimum thicknesses, depending upon the Mullen test and certain other requirements. This is to insure sufficient strength in the entire 35 board.

The corrugated board consists of an inside liner, an outside liner, and between the same is positioned an intermediate portion consisting of a corrugated sheet which, as will be perfectly 40 evident, is arranged to provide maximum resistance in deformation in one direction with reference to the direction of corrugating and which, of necessity, offers minimum resistance to deformation in a transverse direction and offers intermediate 45 resistance to deformation in any direction intermediate the two last mentioned.

The present invention, therefore, is directed to the formation of a container in substantially the same manner as is now conventionally employed but having certain novel features which may be briefly summarized as follows:—

When the intermediate portion of the board, hereinafter to be set forth more fully, is utilized and is of the specific character set forth as "indented," there results a board which has sub-

stantially uniform resistance in all directions as distinguished from one direction resistance of the corrugated board. There also results a saving in this respect, that in this indented portion of the ultimate board, if formed from premade board which consists of a flat sheet of finished paper, the area of the finished indented board is substantially equal to the area of the initial smooth board or finished sheet utilized, which, as will be most obvious, is not the case when a 10 corrugated board is employed for the reason that the act of corrugating results in the corrugated sheet with respect to its overall length in the direction of the corrugating, being approximately two-thirds or thereabouts of the initial board or 15 sheet utilized. As set forth in the co-pending application, Serial No. 694,782, filed October 23, 1933, so-called dry indenting or indenting of flat finished board is disclosed.

The so-called "wet-process" of indenting produces a board which is subject to the objections mentioned in said copending application. However, certain phases of the present invention are not restricted to the formation of the indented board by the process set forth and claimed in the 25 co-pending application last mentioned, but apply as well to the use of indented board formed by the so-called "wet-process" described therein.

The advantage of using dry indented board is that relatively deep indentations can be formed in 30 the board and that the intermediate portion between the liners may be built up of one or more plies of this indented board sufficient to provide the desired thickness in the board so that the 35 desired thickness can be obtained for the various container requirements. In other words, there results a board of substantially the same thickness and strength as the solid fibre board and as distinguished from the corrugated board utilizes but approximately two-thirds in area of the originally 40 necessary, intermediate layer forming flat sheet material and also provides uniform stress accommodation in all directions. This results in a very material decrease in weight in both comparisons, which results obviously in a material 45 reduction in the cost of production by reason of reduction in cost of raw material and secondly, in the reduction in transportation charges which are based upon weight.

Another object of the invention is to provide a 50 container, if and when desired, with an interior liner which is of an indented character. The purchaser, if he intends to ship canned goods, can utilize this container with reasonable assurance that if any deformation in shipment occurs in the 55

container, it will not permit the several cans in the box to have very much freedom. This freedom is highly objectionable because if a corrugated board box is employed, the corrugations, 5 as stated, may be crushed more readily in a direction transverse to the direction of strength. This crushing provides considerable additional room in the container so that the cans can move to and fro during shipment, resulting in damage to the 10 cans, resulting in "leakers," as well as damage to the labels. With a solid ply board box, the cans rub against each other and any deformation from the exterior will be immediately transmitted to the can immediately adjacent the interior. Fur- 15 thermore, the cans, since the board is smooth, rub one against the other, resulting in displacement or rubbing of the label. Pyramiding of cans also brings unusual strains or stresses against the end and side walls which are most effectively 20 accommodated by the present invention and not so effectively accommodated by smooth lined or corrugated board containers.

The present invention by providing an indented liner for a container does two things. First, it 25 provides a cushion which will absorb external forces applied to the carton or container, and second, and more important, the interior liner will nest, or lock, as it were, the chimes of the cans so that if there are two layers of cans, the bottom 30 will nest the lower chimes of the lower layer and the top will nest the upper chimes of the upper layer, thereby holding the cans against displacement or movement in the container. If more than one layer is to be packed, thin spacing boards 35 may be utilized which could have indentations upon one or both sides and thus the adjacent chimes of the adjacent superposed cans would also be nested by said indented board.

The present invention, therefore, is directed to 40 two phases—first, a paper board container having an indented inner lining and second, a paper board container having an indented intermediate 45 ply portion of the desired thickness. It will also be obvious that a container embodying both features last mentioned may be employed, if and when desired, and it will also be obvious that if and when desired, instead of the container having a smooth exterior, it may, instead be provided with an indented exterior so that the adjacent 50 cartons in shipment will more or less interlock together and prevent their relative weaving, shifting, or side-to-side movement and will also provide additional cushioning.

A similar "locking" advantage of an inner in- 55 dented lined container is provided for glassware and other products of a fragile nature. The usual partitions in the present instance, as well as the articles, are locked in ideal position against displacement by the indented inner liner of the top 60 and bottom of containers, also cushioned against side and end wall shocks and the indented partitions maintain the ideal original arrangement and formation of contents.

The full nature of the invention will be under- 65 stood from the accompanying drawings and the following description and claims:—

In the drawings, Fig. 1 is a central sectional view of a plurality of superposed containers, each containing a plurality of layers of cans and hav- 70 ing an indented exterior, an indented interior and indented spacer.

Fig. 2 is an enlarged transverse sectional view of a corrugated board provided with single indented and smooth liners.

75 Fig. 3 is a view similar to Fig. 2, illustrating a

board having a smooth liner, a double indented intermediate portion and a single indented exposed liner.

Fig. 4 is a similar view of a board wherein an intermediate flat ply is interposed between the 5 double indented intermediate portion and the single indented exposed liner.

Fig. 5 is a view similar to Fig. 2 with the addition of a flat ply between the corrugated board portion and the single indented liner. 10

Fig. 6 is a similar view of an indented board showing single indented liners upon both sides of a corrugated intermediate portion and with smooth plies interposed therebetween.

Fig. 7 is a similar view of a multiply indented 15 board, wherein the two exposed liners are of single indented character and the intermediate portion is a double indented ply with two smooth intermediate plies.

Fig. 8 is a view similar to Fig. 7 but illustrates 20 the employment of a plurality of double indented sheets to comprise the intermediate portion between two exposed indented liners, although the smooth plies are omitted.

Fig. 9 is an enlarged central sectional view 25 through one end of a can and the associated board, showing the chime interlocking with the indentation or embossment.

Figs. 10 to 16, inclusive, are views similar to Fig. 1 with parts broken away, the container in 30 each figure including the board illustrated in Figs. 2 to 8, inclusive, respectively.

Railroad specifications covering shipping containers specify that some of the so-called solid fibre containers for a certain dimension limit and 35 gross weight limit be built with board ".060" in thickness and withstand 175 lbs. Mullen test, and that a container of a similar character for larger dimension limits and higher weight limits be made of board with a caliper or thickness of 40 ".080" and withstand 200 lbs. Mullen test. By using materials having a higher Mullen or tear test per point of caliper than is usually found in solid fibre board, there can be produced by this invention a board for shipping containers 45 having a caliper or thickness equal to the two above-mentioned calipers, or any other given caliper, that will obtain an equal Mullen test and equal carrying capacity, with considerably less weight of board and, consequently, at a lower cost 50 of material.

Now this dual advantage is not so pronounced with respect to the present invention when compared with corrugated board. As compared with corrugated board, as hereinbefore set forth, the 55 advantage consists in providing a board that is uniformly and equally in two transverse directions adapted to accommodate the stress. Furthermore, the mere act of corrugating necessitates the use of approximately one-half more material than is necessary to produce the same intermediate ply, or plies, when formed of indented board and of substantially the same thickness.

In the drawings, 10 indicates a side wall, 11 an end wall, 12 a conventional bottom and 13 a top of a container in which is mounted two layers of cans 14 with an intermediate spacer 15 of indented character, the cans having the chimes 16 that nest in the indented interior 17 and indented spacers or partitions 15. Herein also, the exterior of the board forming the container is indented as at 18. This form of board is illustrated more particularly in either Figs. 6,

7 or 8, to which reference will be had more fully hereinafter.

As hereinbefore set forth, it requires to make a corrugated sheet 12" in length and of uniform width, a flat sheet of approximately 18" in length and of the same width. There is thus a shrinkage, as it were, of approximately thirty-three percent.

As set forth in the co-pending application a flat sheet 12" in length and of the desired width, will produce an indented sheet 12" in length and of the same width, thereby effecting a saving of approximately thirty-three percent for approximately the same volume of board with the added advantage of uniform resistance to stress or cushioning in all directions; whereas, the corrugated structure, before mentioned, has maximum resistance in one direction, minimum resistance in a transverse direction and varying degrees of resistance therebetween in intermediate directions.

As shown in Fig. 1, the chimes of the can nest in the indented interior or liner and thus prevent displacement of the can in the carton. Likewise, the exterior liner 18 permits adjacent containers to relatively interlock one with the other and prevents relative displacement therebetween. All of this is an advantage in the shipment of canned goods, since it prevents undue wear on the labels of the cans and also reduces to a minimum what is known as "leakers." As before set forth, a board of this character, when subjected to external strains or stresses, crushes in a localized portion and the same is absorbed in the board and is not transmitted to the cans in the container, as obtains with the solid board container.

The present container also has the advantage the corrugated container has, that it is of lighter weight than the solid board for an equal strength and volume.

In Figs. 2 to 9 various forms of this board are illustrated. In Fig. 2, 20 illustrates a flat liner forming the exterior of a smooth container. The intermediate layer is illustrated as one ply of corrugated board 21 and a third layer is the single indented layer or ply 22. This ply forms the interior of the box. By the words "indented board" is meant board which is either embossed 50 on one side or embossed on both sides and includes said embossments or indentations.

In Fig. 3 there is illustrated a flat liner 30, a double indented intermediate ply 31 and a single indented exposed ply 32. This distinguishes from the form shown in Fig. 2 by the substitution of an indented intermediate portion.

In Fig. 4 there is illustrated another form of board, wherein 40 indicates a flat liner, 41 a double indented intermediate ply, 42 a flat liner and 43 a single indented exposed liner.

In Fig. 5, 50 indicates a flat liner, 51 a corrugated intermediate ply, 52 a flat sheet and 53 a single indented ply.

In Fig. 6, there is illustrated the board having an outer indented ply 60, an intermediate corrugated portion 61, both suitably secured to a flat liner 62, and another indented liner 63 separated from and secured to an intermediate liner 64. Either one or both of the flat liners 62 and 64 may be omitted.

In the form of the invention shown in Fig. 7, 70 indicates the indented exterior liner, 72 the indented interior liner, 71 an intermediate flat sheet, 73 a similar flat sheet, the two flat sheets 75 being spaced apart by a double indented ply 74.

In Fig. 8 there is shown a slightly modified form of the invention, wherein 80 represents the indented exterior liner, 82 the indented interior liner, and 83 and 84 double indented plies that are suitably secured together and secured to the 8 single indented liners.

In each form of the invention illustrated in Figs. 2 to 8 inclusive, it is to be noted there is provided one exposed face of an indented character and in the forms of the invention illustrated 10 in Figs. 6 to 8, inclusive, there is illustrated a board having two exposed indented faces. Whenever desired, additional indented liners may be nestingly associated as well.

Figs. 10 to 16, inclusive, illustrate the board 15 shown in Figs. 2 to 8, inclusive, respectively, in container or carton formation with two tiers of cans in the carton.

In Fig. 10, numerals of the two hundred series indicate parts similarly numbered in Fig. 1 for 20 the carton and cans and similar portions of the board arranged in carton formation bear numerals of the two hundred series similar to the numerals applied to similar portions of the board applied to Fig. 2.

In Fig. 11, numerals of the three hundred series indicate parts similarly numbered in Fig. 1 for the carton and cans and similar portions of the board arranged in carton formation bear numerals of the three hundred series similar to the 30 numerals applied to similar portions of the board applied to Fig. 3.

In Fig. 12, numerals of the four hundred series indicate parts similarly numbered in Fig. 1 for the carton and cans and similar portions of the 35 board arranged in carton formation bear numerals of the four hundred series similar to the numerals applied to similar portions of the board applied to Fig. 4.

In Fig. 13 numerals of the five hundred series 40 indicate parts similarly numbered in Fig. 1 for the carton and cans and similar portions of the board arranged in carton formation bear numerals of the five hundred series similar to the numerals applied to similar portions of the board 45 applied to Fig. 5.

In Fig. 14 numerals of the six hundred series indicate parts similarly numbered in Fig. 1 for the carton and cans and similar portions of the board arranged in carton formation bear numerals of the six hundred series similar to the 50 numerals applied to similar portions of the board applied to Fig. 6.

In Fig. 15 numerals of the seven hundred series indicate parts similarly numbered in Fig. 1 for the carton and cans and similar portions of the board arranged in carton formation bear numerals of the seven hundred series similar to the numerals applied to similar portions of the board 55 applied to Fig. 7.

In Fig. 16 numerals of the eight hundred series indicate parts similarly numbered in Fig. 1 for the carton and cans and similar portions of the board arranged in carton formation bear numerals of the eight hundred series similar to the numerals applied to similar portions of the board 60 applied to Fig. 8.

In each of the forms of the invention shown in Figs. 10 to 16, inclusive, the inner liner is of indented character and the functional feature 70 thereof has been heretofore set forth with reference to the form of the invention shown in Fig. 1.

The forms of the invention shown in Figs. 10 to 13, inclusive, differ from the form of the invention shown in Fig. 1 in that the outside of the 75

carton is of smooth finish, whereas the forms of the invention shown in Figs. 14 to 16, inclusive, differ therefrom and are similar to the form of the invention shown in Fig. 1 in that the outside 5 surface is of roughened or indented character.

While it will be obvious that various forms of the invention may be built up comprising flat sheets, an intermediate cushion layer, and one or more exposed indented layers, and the intermediate 10 cushion layer may be of single and/or double indented character or of corrugated character, and that in certain instances the flat sheet liner, ply, or plies, may be omitted, or more than one ply of indented inner or outer liners may be used, all of these variations, however, are considered to be within the broad scope of this invention, reference being had to the appended claims. It is to be understood the several illustrations herein before specifically mentioned, are merely 15 illustrative in character and are not restrictive in character.

The terminology "unit weight" and "unit strength" used in the claims refers to the actual weight in pounds or ounces per unit of area usually selected for test purposes and the actual strength per similar unit of area as used in the paper board industry.

The invention claimed is:—

1. A paper board container including side and 30 end walls and a top and a bottom, all formed from paper board material in sheet form including an exterior smooth liner and an innermost indented liner having indentations substantially throughout the entire area thereof, each indentation being materially less in area than the cross-sectional area of a chime-ended can in the container, and spaced apart sufficiently to nest a portion of the chime therebetween, the indentations of the innermost indented liner being 35 adapted to engage adjacent chime ends of a plurality of adjacent cans to lock said cans against displacement when packaged in said container irrespective of the indentation outline.

2. A paper board container including side and 45 end walls and a top and a bottom, all formed from paper board material in sheet form including an exterior smooth liner, an intermediate corrugated portion, and an innermost indented liner having indentations substantially throughout the entire area thereof, each indentation being materially less in area than the cross-sectional area of a chime-ended can in the container, and spaced apart sufficiently to nest a portion of the chime therebetween, the indentations of the innermost indented liner being adapted to engage 50 adjacent chime ends of a plurality of adjacent cans to lock said cans against displacement when packaged in said container irrespective of the indentation outline.

3. A paper board container having board therein with a unit strength at least equal to that of a solid fibre paper board container wherein the solid fibre board is substantially of equal thickness, comprising paper board material in sheet 55 form arranged in container formation and including an outer smooth liner or ply, an inner indented liner or ply, and an intermediate unitary non-flat, non-solid ply portion secured to both liners and forming therewith a paper board 60 of materially less unit weight than the unit weight of solid fibre board having substantially the same thickness.

4. A device as defined by claim 3, characterized by the intermediate non-flat, non-solid ply portion comprising an indented sheet, the indenta-

tions projecting therefrom the desired amount to form a board of the desired thickness and from a sheet of finished paper board stock substantially equal in area to the indented sheet.

5. A device as defined by claim 1, characterized by the sheet of paper board having an outermost and exposed indented liner secured to the smooth liner.

6. A device as defined by claim 2, characterized by the sheet of paper board having an outermost and exposed indented liner secured to the smooth liner.

7. A device as defined by claim 1, characterized by the addition of a non-flat liner between the smooth liner and the inside indented liner.

8. A device as defined by claim 1, characterized by the addition of indented material between the indented liner and smooth liner.

9. A device as defined by claim 1, characterized by the sheet of paper board having an outermost and exposed indented liner secured to the smooth liner and by the further addition of a non-flat layer between the smooth liner and the inside indented liner.

10. A device as defined by claim 1, characterized by the sheet of paper board having an outermost and exposed indented liner secured to the smooth liner and by the further addition of indented material between the indented liner and the smooth liner.

11. A paper board container, including side and end walls and a top and a bottom all formed from a sheet of paper board including a non-flat exterior layer, a non-flat intermediate layer and an innermost indented liner having indentations substantially throughout the area thereof, each indentation being materially less in area than the cross-sectional area of a chime-ended can in the container and spaced apart sufficiently to nest a portion of the chime therebetween, said indented portion being adapted to engage adjacent chime ends of a plurality of adjacent cans to lock said cans against displacement when packaged in said container irrespective of the indentation outline.

12. A device as defined by claim 11, characterized by the intermediate, non-flat layer being of corrugated character.

13. A device as defined by claim 11, characterized by the intermediate layer being of double indented character.

14. A device as defined by claim 11, characterized by the intermediate layer including a plurality of indented layers.

15. A device as defined by claim 11, characterized by the intermediate, non-flat layer being of corrugated character, and the addition of a flat liner interposed between the intermediate corrugated layer and the indented innermost inside liner.

16. A device as defined by claim 11, characterized by the intermediate layer being of double indented character, and the addition of a flat liner interposed between the intermediate, double indented layer and the indented innermost inside liner.

17. A paper board container normally more resistant to transverse crushing at the edge than a corrugated board container at the edge parallel to the corrugation, comprising a sheet of paper board stock arranged in container formation and including an outer liner, an inner liner, and an intermediate non-flat, non-solid unitary ply portion secured to both liners and of indented character insuring uniform resistance to localized crushing in substantially all directions, said inter-

mediate ply portion including a plurality of indented plies operatively secured together.

18. A paper board container normally more resistant to transverse crushing at the edge than a corrugated board container at the edge parallel to the corrugation, comprising a sheet of paper board stock arranged in container formation and including an outer liner, an inner liner, and an intermediate non-flat, non-solid unitary ply portion secured to both liners and of indented character insuring uniform resistance to localized crushing in substantially all directions, said intermediate ply portion including a plurality of indented plies, and one of said liners being of indented character, the indented intermediate plies being secured together.

19. A paper board container normally more resistant to transverse crushing at the edge than a corrugated board container at the edge parallel to the corrugation, comprising a sheet of paper board stock arranged in container formation and including an outer liner, an inner liner, and an intermediate non-flat, non-solid unitary ply portion secured to both liners and of indented character insuring uniform resistance to localized crushing in substantially all directions, said intermediate ply portion including a plurality of indented plies, and said liners each being of indented character, the indented intermediate plies being secured together.
